TORPEDO LAUNCHING GEAR

Hubert Scott-Paine, Hythe, England

Application August 31, 1936, Serial No. 98,650
In Great Britain June 20, 1935

7 Claims. (Cl. 114—18)

This application corresponds to the application of Hubert Scott-Paine, Serial No. 17755/35, which was filed in Great Britain on 20th June 1935.

This invention relates to an improved method of and means for launching torpedoes and the like. It is particularly adapted for use on board small high-speed craft, such as for example motor-boats, where the ordinary method of discharging torpedoes cannot conveniently be carried out.

According to the present invention the improved method of launching a torpedo from a high-speed vessel consists in mounting the torpedo upon a downwardly inclined slip-way, and causing a sudden change in the speed of the vessel, whereby the inertia of the torpedo, operative during the acceleration of the boat, causes or assists its launching movement down the slip-way. It will be clear that the more sudden the change in speed, or in other words the higher the rate of acceleration of the boat, the more effective is the inertia in producing the launching movement. The slip-way may be directed forwardly or aft on the vessel and the appropriate negative or positive acceleration is used for effecting the launching.

The invention also includes apparatus for launching a torpedo from a high-speed vessel, comprising a downwardly sloping slip-way, and releasable means for retaining a torpedo thereon against any tendency to slide down until it is required to be launched. According to another feature of the invention, the releasable means for retaining the torpedo in place on the slip-way, may be adapted to be coupled at will to a throttle lever or equivalent device for controlling the speed of the vessel so that the movement of the throttle for changing the speed of the vessel also releases the torpedo at the appropriate moment.

According to yet another feature of the invention the slip-way aforesaid comprises an outboard extension, and separate guides which support the torpedo at two points forward and aft, said guides extending outward to respectively appropriate distances to release the two ends of the torpedo simultaneously or in any other predetermined timing; thus for example it may be desirable to arrange that the forward end of the torpedo falls slightly before the after end so that the torpedo on entering the water immediately dives to its proper depth.

In a preferred construction the outboard extension aforesaid of the slip-way is adjustable from its operative outboard position to an inboard position, where it can be stowed when not in use.

In the accompanying drawings which illustrate this invention diagrammatically,

Figure 1 is an elevation in section on the line

1—1 of Figure 2, of the rear end of a motor-boat showing the slip-way in its operative position and also showing the manner of stowing the outboard extension,

Figure 2 is a plan, partly of Figure 1, and partly showing an alternative arrangement in which the torpedo is reversed so that its forward end is directed aft from the vessel,

Figure 3 is a detail view indicating diagrammatically the construction of the slip-way, and

Figures 4 and 5 are detailed views of the controlling gear.

Referring to these drawings, the torpedo is indicated generally by the reference 10, and in order that it shall move easily on its slip-way, it is provided with guide wheels at each side and spaced apart longitudinally; the forward pair of wheels are indicated at 11 and the after pair at 12. Two pairs of rails or tracks are provided of different gauge, one pair 13 to engage the forward wheels 11 and the other pair 14 to engage the after wheels 12, and these rails are mounted on any suitable structure, indicated generally by the reference 15, which is supported within the boat 16 and near the stern thereof.

The slip-way extends to an opening 17 situated above the water line in the stern of the vessel, and an additional structure 18 is provided to align with it and extend outboard from the vessel; preferably this structure is hinged at 19 so that it can be folded upwards and inwards to the inboard or stowed position when not in use, and it carries rails 13 and 14 to align with and constitute continuations of the corresponding rails on the structure 15.

The structure 15 with the rails 13, 14 is inclined downwardly towards the stern so that a torpedo mounted on it will tend to run down it, and a latch or detent 20 of any suitable form is provided to restrain such movement; conveniently the latch engages the wheels 12, and is held in its locking position against the action of a spring, by a detent which can be released from some remote position, for example by pulling the cord 21 so that when the cord is pulled the latch is released and is automatically swung into its disengaging position to release the torpedo.

The cord 21 is conveniently operated from the control tower or bridge of the vessel and, as illustrated in Figures 4 and 5, it may be secured to a lever 27 mounted beside the throttle lever 28; a pin 29 on the lever 28 is adapted to be moved into the position shown in Figure 5 in which it will engage the lever 27 and move it when the throttle is moved. Normally this pin 29 is retracted to its inoperative position and it is projected to be operative only when the torpedo is to be launched. Any other device may be used which is adapted to be coupled at will to the throttle or

other speed-controlling means on the vessel so as to be simultaneously moved therewith.

It is preferred that check-rails 22 should be associated with each of the rails 13, 14 as shown 5 in Figure 3, to maintain the wheels 11 and 12 always securely in engagement with their running rails.

As will be seen in Figure 2 the rails 14 extend outboard farther than the rails 13, the relative 10 spacing of the ends of the rails being determined by the fore-and-aft spacing of the wheels 11, 12 and the manner in which the torpedo is to be dropped; usually it is desirable that it should be downwardly inclined on entering the water so 15 that it can readily dive to its proper depth, and as shown in Figure 1 the position of a torpedo as it is dropping is indicated at 23; the forward wheels 11 have cleared the end of their rails 13 so that the forward end of the torpedo has dropped 20 slightly, and the after wheels 12 are just on the point of leaving the ends of their rails 14 so that the torpedo will be clear of the vessel.

The discharging of a torpedo with the apparatus so far described consists first in directing the 25 motor-boat towards the target, and then reducing the speed of the boat to any desired extent. The actual discharging is then effected by suddenly opening the throttle and simultaneously releasing the detent 20 so that the torpedo is free on 30 its slip-way. The forward acceleration of the boat is not transmitted to the torpedo, which therefore easily runs down the slip-way until it has dropped into the water astern of the boat. The course of the boat is then quickly altered so 35 that it can retire from its target and leave a clear path for the torpedo, although it will frequently happen that the torpedo submerges itself to such a depth that it would clear the motor-boat which is of comparatively shallow draught.

40 In the lower part of Figure 2 there is illustrated a modified arrangement in which the bow of the torpedo is directed aft from the vessel carrying it; the rails 25, 26 on which it travels are, in this case, also terminated at appropriate points to 45 let the bow fall first, and the only difference in the operation is that the torpedo is aimed by directing the stern of the motor-boat at the target.

It will be appreciated that the drawings accompanying this specification are purely diagrammatic, and the exact details of mechanical construction can be varied without departing from the present invention.

I claim:

1. A marine weapon comprising a light variable 55 speed craft having a torpedo runway thereon relative to which a torpedo may move longitudinally of the craft and of its own length from a normal position to a launching position, a torpedo supported for free relative movement along the runway, 60 way from the normal to the launching position, a latch for restraining the torpedo against relative movement along the runway, and common means for simultaneously releasing the latch and changing the speed of the craft whereby the 65 inertia of the torpedo is utilized to move it from the normal to the launching position.

2. The combination with a water craft, of a 70 torpedo-launching slipway thereon extending in a longitudinal direction with respect to the length of the craft, said slipway having an inboard section of a length slightly greater than the length of the torpedo to be launched, and an outboard extension above the waterline of the craft of a length sufficient to enable the torpedo to be sup-

ported in a generally horizontal position clear of the water until the innermost end of the torpedo is clear of the craft, the said extension being provided with means to support the torpedo as it moves along the runway, said means terminating in such manner that the torpedo drops through the runway when it is clear of the craft. 5

3. The combination with a water craft, of a torpedo-launching slipway thereon extending in a longitudinal direction with respect to the length 10 of the craft, said slipway having an inboard section of a length slightly greater than the length of the torpedo to be launched, and an outboard extension of a length sufficient to enable the torpedo to be supported in a generally horizontal 15 position clear of the water until the innermost end of the torpedo is clear of the craft, said outboard extension being hinged to move from the outboard position to an inboard position.

4. The combination with a small craft, of a 20 torpedo-launching slipway carried thereon and a torpedo, the torpedo being provided with fore and aft rollers, the slipway comprising a supporting structure having two sets of rails, one being engaged by the forward rollers of the torpedo and 25 the other being engaged by the aft rollers of the torpedo, both sets of rails extending outboard a sufficient distance to support the torpedo until it is moved to a position clear of the craft, the former rails being extended a shorter distance 30 than the latter.

5. The combination with a small craft, of a 35 torpedo-launching slipway carried thereon and a torpedo, the torpedo being provided with fore and aft rollers, the slipway comprising a supporting structure having two sets of rails, one being engaged by the forward rollers of the torpedo and the other being engaged by the aft rollers of the 40 torpedo, both sets of rails extending outboard a sufficient distance to support the torpedo until it is moved to a position clear of the craft, the former rails being extended a shorter distance than the latter, and a latch for normally restraining the torpedo from movement along the slipway and in an inboard position relative to the 45 craft.

6. The combination with a high speed water 50 craft, of a downwardly sloping slipway, a torpedo normally carried at the upper end of the slipway, releasable means for restraining the torpedo against movement down the slipway, said slipway having an outboard extension with separate guides to support the torpedo fore and aft, respectively, the guides extending outboard to appropriate distances to release the two ends of 55 the torpedo in predetermined order.

7. A marine weapon comprising a small craft 60 designed to operate from a range of speed and capable of quickly accelerating, a torpedo-launching slipway on the craft extending in a longitudinal direction relative to the longitudinal axis of the craft, a torpedo, antifriction rolling means spaced longitudinally of the torpedo engaging the slipway to assure free rolling movement of the torpedo along the slipway, the slipway sloping 65 downwardly and outwardly, the slipway being above the waterline throughout its length, the slipway and antifriction means being arranged to support the torpedo in a generally horizontal position and clear of the water until it is clear 70 of the craft, and latch means for normally holding the torpedo at the upper end of the slipway.
